HENRI HENNEBUTTE AND EDOUARD GOUTAL, OF PARIS, FRANCE.

APPARATUS FOR EFFECTING CHEMICAL REACTIONS.

Application filed May 21, 1923, Serial No. 640,578, and in France June 7, 1922.

This invention relates to apparatus for effecting chemical reactions and more particularly to an apparatus which is adapted for carrying out dehydration, distillation, or generally speaking, any chemical reactions including:

1st.—Either pyrogenetic decompositions, with or without the addition of reagents.

2nd.—Or oxidations, reductions, hydrogenations sulphurations, and in a general manner any reaction requiring the use of various chemical agents, in such conditions that balancing effects may be effected by stages within required and definite limits of temperature.

3rd.—Or these two kinds of operations which can take place simultaneously or successively in the apparatus.

This apparatus essentially comprises:—

1st.—A stirring device, substantially constituted by one or several endless screws, worms, or translating propellers operated or driven from the inside and located in metal troughs which are simple or twin; these screws are provided with special devices so as to turn over the material and to submit the different parts or members to the reagent and to the action of heat, and also to slow down the progress thereof for instance in bringing or carrying part of the matter backwards.

The screw may be provided for this purpose either with vanes or mould-boards extending from one coil to the other and showing the form of a curved surface so as to constitute a ladle or scoop capable of turning over the matter upon itself, or provided with ports or holes, the part of the metal stamped so as to provide these holes being turned up and curved so as to form a sort of plough-share in order to constitute a sort of mould-board adapted to turn over the matter submitted to the reaction, the latter being permitted to flow rearwardly through the orifice or hole provided in the screw.

The conveyor may, if desired, consist of a simple screw or propeller having a greater or smaller number of holes or divided if necessary into sections so as to form blades or paddles as in a ship propeller;

2nd.—Lids which cover the metal troughs and fit snugly upon the latter, these lids or covers being provided with large exhaust openings and being interiorly provided with

gutters receiving the partially condensed products so as to convey the same outside withdrawing them from the action of the walls in contact with the reacting materials without allowing them to fall back into the part where the reaction takes place. In 55 order to carry out the dehydration and the pyrogenetic decomposition, each trough constitutes a member of a furnace heated to a determined temperature. The material to be treated is placed within these members 60 through which it passes from one to the other, the members being heated at different temperatures. The products which are evolved at the temperatures of the various members are drawn therefrom prior to the 65 passage of the treated material into the next member.

The number of troughs or members, which form reaction stages, can, in this way, be extended in accordance with the physical or 70 chemical changes that it is desired to make in the material treated.

During the operation it is possible to introduce into the members any solid, liquid or gaseous product, which is caused to react 75 upon the matter under treatment, the resulting products being always exhausted in the same conditions.

The accompanying drawings show, by way of examples, several embodiments of the 80 present invention wherein, the arrangement of the troughs as well as the pitch and the speed of the screws in every member can vary in a very large proportion according to the nature of the bodies to be treated and the product which it is desired to obtain.

Figs. 1 and 2 show in side view and in 85 end view respectively a form of construction of the screw or propeller provided with vanes or mould-boards.

Figs. 3 and 4 are a side elevation and end view respectively, illustrating a screw in which the coils or windings are provided with holes and in which the metal is so folded so as to form a mould-board.

Fig. 5 is an end view of a screw of which the coils are simply provided with holes in a larger number than in the previous example.

Fig. 6 is an end-view of a modified form 100 in which the helical surface is divided in sections and forms a screw or propeller with paddles or blades.

Fig. 7 is a longitudinal sectional view illustrating the arrangement of three of the closed troughs or members in series.

Fig. 8 is a sectional view taken on the line X, X of Fig. 7.

Fig. 9 is a horizontal section of the brick-work support showing the arrangement of the partitions or walls acting as baffles.

Fig. 10 shows in cross-section the whole of a second arrangement comprising an inclined furnace or oven for fractional distillation, each part of which is heated to a different temperature, the higher temperature being that of the lowest members.

Figure 11 is a perspective view illustrating the members constituting one stage of the apparatus shown in Fig. 10, Fig. 12 is a top plan view of the apparatus shown in Fig. 11, the covers for the same being removed.

Figs. 13 and 14 are detail sectional views taken on the lines Y, Y and Z, Z respectively, of Fig. 12.

Fig. 15 is a section taken on the line Y¹, Y¹ of Fig. 13, illustrating the preferred form of cover employed.

Figs. 16 and 17 show in plan and in cross-section respectively the covers acting as a diaphragm.

Fig. 18 is a cross-section on a larger scale of a distributor which is interposed between two screws with the purpose of insulating one or more members.

Figs. 19 and 20 show respectively a longitudinal elevation and a plan, the covers or lids being removed in the latter figure of another arrangement in which the members are disposed side by side, a distributor insuring the feeding of each member.

Fig. 21 is a sectional view somewhat enlarged, taken on the line Z¹, Z¹ of Fig. 19.

The screw or propeller, as shown in Figs. 1 and 2, is constituted, like endless screws or worms, by coils or windings forming an helical surface a.

Between the coils are arranged the mould-boards b extending from one coil to the other.

These mould-boards or vanes must have, as it has been above specified, the form of a ladle or scoop in order to turn over the matter and simultaneously bring it partially backwards during the revolving motions.

The screw which is shown in Figs. 3 and 4 is provided, in the surface a forming the coil, with holes c, the metal removed with the purpose of forming these holes being folded so as to constitute small ploughshares or mould-boards d of a suitable shape to turn over the matter undergoing reaction. Due to the differences in pressure between the front and rear faces of the helical surface a, a portion of the treated material will pass rearwardly through the openings or

holes c; these two systems of screw or propeller therefore allow to obtain a delayed progressive motion so that notwithstanding the ordinary speed of revolution of this kind of screws or worms, the matter which is turned over and returned backwards progresses but slowly and consequently is thoroughly submitted to the action of the heat.

The same result can be obtained by the use of an endless screw or worm provided with holes c¹ of suitable sizes and proportions, Fig. 5, or in dividing the helical surface in two sections or paddles c² in the same manner as in a ship-propeller.

The apparatus represented in Figs. 7 and 8 is constituted by a sequence of simple metal troughs A¹, A¹, A², the axes of which are slightly inclined and which are covered with lids B¹, B², B³ the screws revolving in the troughs are the same as those which have been described with reference to Figures 1 and 2, 3 and 4 or 5 or 6, driven by gear-wheels e, chains or any other transmission means.

The lids or covers B are provided internally with an inwardly extending flange which is curved upwardly to form a gutter f for collecting the products of condensation evolved in the troughs A. An opening or port g is preferably provided at the lowest point of the gutters f to serve as a drainage passageway for said products. The bottom of each of the inclined troughs is provided adjacent the higher end thereof with an opening h which constitutes a connecting passageway to the lower part of the next adjacent trough. The covers of the troughs are provided with one or more openings i in communication with suitable pipes k which preferably lead to a condenser or collecting chamber.

The trough A³ is provided at its lower portion with an opening C for the exhaust of the carbonized matter which can be utilized if necessary as a fuel for heating the apparatus.

This member or trough A³ is heated by means of gas coming from a generator or from a furnace in which the circulation is insured by baffle-plates G as is clearly illustrated in Fig. 9.

The gases passing under a flue D arrive under the member A¹ on their way to the stack; the first member A¹ is provided with an air-tight charging hopper E provided with a flap-door or other suitable shutting device.

The apparatus, as shown in Figures 10, 11 and 12, comprises twin metal troughs m, n horizontally arranged at different heights, and separated by a hollow partition o of convenient form, Figs. 10 and 13, which partition o terminates at a short distance from either end of the troughs to form a passage p. Each of these troughs contains a screw cut in

the middle into two parts to each of which a movement is imparted in a reverse direction, or a single screw α the coils of which are divided into two parts having reverse pitches, as is illustrated in Fig. 12.

Every member thus constituted is covered with a lid q showing in a cross-section the form which is represented in Fig. 13 and in the right-hand portion of Fig. 10, so as to constitute an inclined arch. The lids q are provided with edges or peripheral gutters f , at the lower parts close to the joints, so as to collect the condensed products.

In order to avoid a direct connection between the two contiguous troughs of the same member, there is arranged at the middle of the latter a sort of hood u provided with a diaphragm v .

The matter to be treated enters through the hood u in the middle of the troughs whence it is forced in both directions, as shown by the arrows F^1 , into the two symmetrical parts of the apparatus under the action of the first screw α , passes through the channel p , is taken over by the second screw α which conveys it back in the direction indicated by the arrows F^2 , towards the middle of the member where it passes through a central conduit r into the second juxtaposed member. In order to completely prevent the gases generated in one of the members from mixing with the gases of the members situated immediately above, there is arranged between two members an alveolar distributor or drum L , as shown in Figs. 10, 18, and 21. The matter to be treated progresses from the top to the bottom, as shown in Fig. 10.

The gases due to distillation which are not condensed and collected by the gutters or grooves f are collected through the orifices j , as shown in Figs. 7 and 11, scattered in the high portion of the lid and connected through joints k with a pipe t leading to a condenser.

The apparatus of Fig. 10 is illustrated as a sort of hut having the shape of a triangular hood under which arrive burning gases; the circulation of the said gases is insured by means of flues H and baffle plates J suitably distributed so that the said circulation will take place upwardly, in order that the hottest gases may come into contact with lowermost troughs and the coldest ones with the uppermost troughs. This insures a rational heating and a mechanical exhaust; the gases then escaping through the orifice K whence they pass to the stack.

These apparatuses are so arranged that each member or trough will be heated at a different temperature, the higher temperature being that of the last member; the products submitted to the pyrogenetic decomposition move in a direction reverse to that of the gases which heat the apparatus and the generated gaseous products are directly exhaust-

ed thereby avoiding any contact with the heating walls by virtue of the arrangement of the covers or lids provided with gutters which prevent the condensed products from dropping back into the troughs.

70

The uncondensed distillation products of these members are exhausted, as already seen, through the holes provided at the upper part of the covers, while the condensed products are discharged through openings provided at the lowest points.

The third modified form shown in Figures 19, 20 and 21 is constituted by a series of troughs A , the inclination of which varies. The progress of the material is always directed upwardly by means of the screw α and the matter is discharged into the following trough through the medium of compartment M provided at the ends of the apparatus and connecting the upper end of a trough with the lower end of the following one, these compartments forming passages in which revolve the alveolar distributors L . Said distributors are constituted by rotating tubes provided with radial blades. The material accumulates in the space between two adjacent blades and fills said space, and by the rotation of the blades the material is delivered to the adjacent trough without allowing the gases to pass. The drawing shows only two troughs arranged side by side but the number of these troughs is not limited and depends upon the number of stages which the materials under treatment have to pass through.

80

These two troughs are covered by covers q forming an arch or vault and are provided at their lower part, in the vicinity of the joint, with gutters f with an outlet, at the lower point, for the condensed products which have been collected by these gutters and at the higher points with a suitable number of outlets k for the exhaust of the uncondensed gaseous products.

85

Every simple inclined member can be separately covered by means of a lid q as specified with reference to the example shown in Figs. 7 and 8, or the covers or lids of two members arranged the one above the other can be grouped two by two, so as to form a single piece, the common partition w of which would be immersed in a gutter α containing a liquid so as to form a water-seal, as shown in Figure 21.

90

The utilization of this apparatus is quite similar to that of the previous ones. The material is introduced into the first member through the hopper E , progresses under the action of the screw α , is discharged into the middle compartment M in passing through the distributor L , which conveys the same into the beginning of the second member in which it is collected by the screw, and so on.

95

It is obvious that the different arrangements have been here described but by way

of example and that they may be altered as well as regards the arrangement of the troughs, of the lids or covers, of the openings for the condensed and gaseous products, 5 as regards the provision of the circulation of gases under the troughs, without departing from the principle of the present invention.

What we claim is:

- 10 1. Apparatuses for effecting chemical reactions comprising troughs inclined and arranged side by side, endless screws within the said troughs for propelling the matter to be treated, inclined lids closing the troughs, gutters extending around the periphery of the lids, chambers arranged between two successive troughs for connecting the said troughs, distributors arranged within the chambers for guiding the matter from the preceding trough to the following one and to prevent the gases from passing from one trough to the following one.
- 15 2. An apparatus for effecting chemical reactions comprising a plurality of inclined troughs arranged side by side, endless screws within said troughs for propelling the material to be treated therethrough, convex covers for said troughs, said covers being provided with inwardly extending peripheral gutters and with discharge openings communicating with lowest portion of said gutters, distributors between each pair of troughs for forcing said material from one trough to the other and sealing means between said troughs and covers.
- 20 3. A device of the class described comprising a plurality of inclined troughs in communication one with the other, endless screws in each of said troughs for propelling the matter to be treated therethrough, convex covers for said troughs said covers being provided with inwardly extending peripheral gutters and with discharge openings communicating with lowest portion of said gutters, distributors between each pair of troughs for forcing said material from one trough to the other and a water seal between said troughs and covers.
- 25 4. A device of the class described comprising a plurality of inclined troughs in communication one with the other, endless screws in each of said troughs for propelling the matter to be treated therethrough, convex covers for said troughs said covers being provided with inwardly extending peripheral gutters and with discharge openings communicating with lowest portion of said gutters, distributors between each pair of troughs for forcing said material from one trough to the other and a water seal between said troughs and covers.
- 30 5. A device of the class described comprising a plurality of inclined troughs in communication one with the other, endless screws in each of said troughs for propelling the matter to be treated therethrough, convex covers for said troughs said covers being provided with inwardly extending peripheral gutters and with discharge openings communicating with lowest portion of said gutters, distributors between each pair of troughs for forcing said material from one trough to the other and a water seal between said troughs and covers.
- 35 6. A device of the class described comprising a plurality of inclined troughs in communication one with the other, endless screws in each of said troughs for propelling the matter to be treated therethrough, convex covers for said troughs said covers being provided with inwardly extending peripheral gutters and with discharge openings communicating with lowest portion of said gutters, distributors between each pair of troughs for forcing said material from one trough to the other and a water seal between said troughs and covers.
- 40 7. A device of the class described comprising a plurality of inclined troughs in communication one with the other, endless screws in each of said troughs for propelling the matter to be treated therethrough, convex covers for said troughs said covers being provided with inwardly extending peripheral gutters and with discharge openings communicating with lowest portion of said gutters, distributors between each pair of troughs for forcing said material from one trough to the other and a water seal between said troughs and covers.
- 45 8. A device of the class described comprising a plurality of inclined troughs in communication one with the other, endless screws in each of said troughs for propelling the matter to be treated therethrough, convex covers for said troughs said covers being provided with inwardly extending peripheral gutters and with discharge openings communicating with lowest portion of said gutters, distributors between each pair of troughs for forcing said material from one trough to the other and a water seal between said troughs and covers.

be treated therethrough, convex covers for said troughs, said covers being provided with inwardly extending peripheral gutters and with discharge openings communicating with lowest portion of said gutters, and distributors between each pair of troughs for forcing said material from one trough to the other.

9. A device of the class described comprising a plurality of troughs in communication one with the other, endless screws in each of said troughs for propelling the matter to be treated therethrough, convex covers for said troughs, said covers being provided with inwardly extending peripheral gutters and with discharge openings communicating with lowest portion of said gutters, distributors between each pair of troughs for forcing said material from one trough to the other and sealing means between said troughs and covers.

10. A device of the class described comprising a plurality of troughs in communication one with the other, endless screws in each of said troughs for propelling the matter to be treated therethrough, convex covers for said troughs said covers being provided with inwardly extending peripheral gutters and with discharge openings communicating with lowest portion of said gutters, distributors between each pair of troughs for forcing said material from one trough to the other and a water seal between said troughs and covers.

11. A device of the class described comprising a plurality of inclined troughs in communication one with the other, endless screws in each of said troughs for propelling the matter to be treated therethrough, convex covers for said troughs said covers being provided with inwardly extending peripheral gutters and with discharge openings communicating with lowest portion of said gutters, and distributors between each pair of troughs for forcing said material from one trough to the other.

In testimony whereof we have signed this specification.

HENRI HENNEBUTTE.
EDOUARD GOUTAL.
